UNITED STATES PATENT OFFICE.

JOSEPH DANNHEISER, OF SAN FRANCISCO, CALIFORNIA.

FILING-CABINET.

941,133.

Specification of Letters Patent. Patented Nov. 23, 1909.

Application filed December 4, 1908. Serial No. 465,927.

To all whom it may concern:

Be it known that I, JOSEPH DANNHEISER, citizen of the United States, residing in the city and county of San Francisco and State 5 of California, have invented new and useful Improvements in Filing-Cabinets, of which the following is a specification.

My invention relates to filing cabinets.

My object is to provide a cabinet suitable 10 for filing drawings and the like in vertical position, in which the drawing will be suspended in a pocket, and with means for withdrawing any desired drawing when the cabinet is opened, and opening out the drawing 15 ready for inspection and use.

It has other objects which will be manifest hereinafter.

The invention consists of the parts and 20 the construction and combination of parts as hereinafter more fully described and claimed, having reference to the accompanying drawings, in which—

Figure 1 is a vertical section of my filing cabinet. Fig. 2 is a front elevation of same, 25 partially broken away. Fig. 3 is a plan view of same. Fig. 4 is a broken away perspective showing the clamp and filing pocket. Fig. 5 shows a modification of the clamping device. Fig. 6 shows one way of 30 attaching an index card holder. Fig. 7 is a detail of the spring members 16.

A represents a cabinet or box of any suitable size, shape or material, and having a top cover 2, and a front door or closure 3; 35 this closure 3 being slideable and pivotally supported by the braces 4 to the lower end of the closure and provided with pivot pins 5 which operate in the guide slots 6 in the sides of the cabinet. The outward movement of 40 the closure or panel 3 and of the brace arms 4 is limited by suitable means, as the slotted segment 7.

The maps, drawings, or other papers to be 45 filed are held by clamp members 8—9 carried by rods 10, and which rods are adapted to rest on a cross-piece 11 and behind a stop-bar 12 in the top of the cabinet.

The clamp members 8—9 are made of sheet-metal, one of the members, as 8, being 50 bent around a rod 10 to embrace the latter and to turn thereon, and the other member 9 being bent around both the bent portion of the member 8 and the rod, and adapted to have a limited turning movement toward 55 and from the coöperating member 8; this

limiting movement being provided for by having the bent portion of the outer member 9 extend a little less than the full circumference around the bent portion or pivot of the member 8. The two members 8—9 are 60 locked together to grip a sheet, by suitable means, as the rigid loop member 13.

Secured to one of the members, as 8, is a pocket 14 made of any suitable material, like tough manila paper, with the two ends 65 of the strip brought together and locked by suitable means, as the glove fastener 15, adjacent to the lower edge of the grip member 9. The papers or maps or drawings to be filed are placed inside the pocket 14 and 70 gripped by the members 8—9, when the clamping device 13 is slipped down over the members 8—9. There may be any number of these rods with their respective grippers 75 8—9 and pockets 14, each pocket containing 75 separate maps or memoranda, and all these pockets or filing devices are slipped into place in the cabinet from the top, with the ends of the rods 10 projecting beyond the 80 pockets and resting, as before said, on the cross-pieces 11.

Extending across each end of the cabinet just above the cross-pieces 11 is a spring plate 16 which is slit and bent, as shown at 17, to provide spring catches, each of which 85 spring catches 17 projects a short distance inwardly over the end of a respective hanger rod 10. The disposition and length of the spring catches 17 are such that if any one of the hanger rods 10 is lifted, a pair 90 of these spring catches 17 will be spread outward to allow the rod to pass up, and then spring in again immediately to form a support for the rod, above, and parallel with, 95 the lower support 11.

If now the front panel 3 is opened, assuming it previously to have been closed and with the hook members 18 pushed into full line position within the cabinet, as shown in Fig. 1, the withdrawal outward of the panel 3 into operative horizontal dotted line position, will cause the hooks 19 on the ends of the members 18 to engage the ends of the lifted hanger rod and draw it forward and withdraw the particular pocket and drawing carried by that rod. The act of withdrawing the drawing from the cabinet bends the pocket so that the fastening 15 may be loosened, and the act of opening out the panel 3 110 opens the pocket and spreads the drawing

flat on the table. In this operation the stop-bar 12 prevents the other rods from being disarranged.

The rods 18 have a free sliding movement 5 in the ends of the panel 3, and their length is approximately equal to the depth of the box. When the panel 3 is closed these rods are pushed into place out of sight and in 10 behind the hangers, substantially, as shown in full lines, Fig. 1. In practice, the hooks will drop down when the panel 3 is in horizontal position, presenting a free and unobstructed table for use as a drawing table.

To replace a file, the pocket is buttoned up 15 and the file slipped down into place, the springing out of a pair of spring catches 17 allowing the hanger once more to assume its position, being supported on the cross-bars 11.

20 The various hanger rods are provided with suitable indexes 20 arranged in any appropriate manner.

In Fig. 5, I have shown a modified form 25 8' of the clamping device, in which the clamp member is formed from one piece of sheet-metal. The paper forming the pocket is fastened, as shown, by folding the paper around the bar, the clamp member 8' being bent around the rod outside of the paper, 30 clamping this in place.

Having thus described my invention, what I claim and desire to secure by Letters Patent is—

1. In a filing cabinet, the combination of 35 a box having a front panel, with means for turning this panel from a vertical to a horizontal position, filing devices supported in the upper portion of the cabinet, and means carried by the panel engageable with one of 40 said filing devices to withdraw the same from the cabinet and spread it on the table.

2. A filing cabinet comprising a box having a movable front and top, filing devices supported in the upper portion of the cabi-

net, said filing devices including rods having file-holding means, means for supporting the ends of the rods in the cabinet, other means for supporting the ends of any rod at an elevated position from the other rods, and means carried by the movable front of 50 the box for withdrawing the file of an elevated rod.

3. A filing cabinet comprising a box having a movable front and top, filing devices supported in the upper portion of the cabinet, 55 said filing devices including rods having file-holding means, means for supporting the ends of the rods in the cabinet, and spring catches in the cabinet and above said means for supporting the rods and normally 60 extending over the ends of said rods and interposed in the path thereof, and on which catches a rod may be supported in elevated position.

4. A filing cabinet comprising a box having a movable front and top, filing devices supported in the upper portion of the cabinet, 65 said filing devices including rods having file-holding means, means for supporting the ends of the rods in the cabinet, 70 spring catches in the cabinet and above said means for supporting the rods and normally extending over the ends of said rods and interposed in the path thereof, and on which catches a rod may be supported in elevated 75 position, the front of said box comprising a panel turnable from a vertical to a horizontal position, and means carried by this panel for engaging an elevated rod and withdrawing it from the box when the panel is opened 80 out.

In testimony whereof I have hereunto set my hand in presence of two subscribing witnesses.

JOSEPH DANNHEISER.
